SURFACE CONDENSER

Victor A. Miller and Charles S. Olson,
Duluth, Minn.

Application January 11, 1937, Serial No. 120,006

5 Claims. (Cl. 257—28)

Our invention relates to means and method for automatically removing air pockets from surface condenser water boxes, such as used in connection with turbine engines or the like, or automatically controlling the height of water from other containers in which a vacuum is maintained.

The principal object of the invention is to provide a simple device of this character and one operable by a vacuum.

Other objects and advantages of the invention will appear in the following description thereof.

Referring now to the accompanying drawing, forming part of this application, and wherein like reference characters indicate like parts:

The figure is a diagrammatic view, partly in elevation and partly in section, illustrating one end of a condenser water box as associated with a turbine engine.

Referring now particularly to the figure, the numeral 1 represents the vacuum side of a standard turbine condenser and 2 the water box at the entrance and discharge side of the condenser, 3 representing the intake of the water box and 4 the discharge thereof.

It has been determined that in such a device the efficiency of a condenser of this type is materially reduced by the collection and trapping of air in and about that portion of the box 2 in close proximity to the connection of the discharge 4, and to dispense with such trapping of air is the principal object of the invention. To this end a container illustrated at 5 is conveniently positioned near the water box 2, and in which sufficient water is maintained to nearly fill the standpipe 6, its lowermost end being installed within

said container 5, which latter is provided with an overflow pipe 15 somewhat below the upper terminus thereof. The standpipe 6 is somewhat longer than required to maintain a column of water 34' 6" in height, this being the normal height of

water maintained by atmospheric pressure in a vacuum. At the upper end of the standpipe is attached the trap 7, having a depending division wall or baffle 8 therein, extending downwardly a considerable distance therein and below the lateral intake pipe connection 9 upon one side of the trap, while upon the opposite side of the baffle and through the top of the trap is the air suction pipe 10, its opposite end communicating as at

11 with the interior of the vacuum side of the condenser 1. In this suction pipe is installed a control valve 12, and a similar control valve 13 is installed within the intake pipe 9 to the trap 7 intermediate of the condenser box and orifice connection 14, this latter being established only after

sufficient experimentation to determine the proper size for such orifice connection.

It will be noted that a portion of the water tubes in the condenser is illustrated at 16, there being a nest of such tubes extending from the water box at the opposite end not shown to that illustrated at 2.

From the above it is apparent that when the device is connected as shown with the valves 12 and 13 open and the orifice connection properly made that the vacuum within the condenser will tend to produce a like condition in the trap 7 which will raise the water in the standpipe 6 in proportion to the number of inches of such vacuum and simultaneously produce suction in the branch pipe 9 from the trap leading to the dangerous zone adjacent the water discharge of the condenser water box, thus freeing the discharge from trapping of any air therein. As the air with possibly some water is discharged into the trap 7 such discharge will fall, the water by gravity into the standpipe 6, and the air therewith to below the baffle 8 when it will be drawn upwardly and through the pipe 10 into the vacuum side of the condenser. As the column of water in the standpipe increases in volume it will obviously be cared for by gravity through the well 5 and its overflow pipe 15.

Having thus described our invention, what we claim and desire to secure by Letters Patent, is:

1. The combination with a receptacle wherein a vacuum is maintained and a container subject to air pockets therein, of means operable by the vacuum in said receptacle for removing said air pockets, said means comprising a trap, a connection from said receptacle to said trap, a connection from said container to said trap, and a hydrostatic column depending from said trap into a body of water, whereby the suction of the vacuum in said receptacle automatically removes air pockets from said container.

2. Means for removing air pockets from the cooling water box of a surface condenser by the vacuum maintained therein, said means comprising a trap, a controlled connection from said trap to said water box, a controlled connection from said trap to the vacuum side of said condenser, and a hydrostatic column depending from said trap and extending into a receptacle having an overflow therefrom, whereby air pockets within said water box will be drawn to the condenser by the vacuum maintained therein.

3. Means for removing air pockets from the cooling water box of a surface condenser comprising a trap, a connection from said trap to said water box, a connection from said trap to the

vacuum side of said condenser whereby the vacuum therein will draw air thereto through said connections and trap from the water box, a hydrostatic column depending from said trap, and 5 a well into which the lower end of said column extends.

4. Means for removing air pockets from the cooling water box of a surface condenser comprising a hydrostatic column adapted to extend 10 into a body of liquid, a connection from the vacuum side of said condenser to the upper end of the hydrostatic column, and a connection from the water box to the upper end of said hydro- 15 static column, whereby air pockets within said

water box will be drawn to said condenser by the vacuum maintained therein.

5. In a surface condenser, the combination with the condensing chamber thereof wherein a vacuum is maintained and the cooling water box 5 thereof subject to air pockets therein, of a connection from said condensing chamber to said water box whereby the suction of the vacuum in said chamber will draw air from the water box, a trap in said connection for separating any 10 water that may be drawn with the air from the water box, and a hydrostatic column maintained by said vacuum and depending from said trap.
